[57] **CLAIM**

The ornamental design for an object holder for pegboard mounting, substantially as shown and described.

DESCRIPTION

FIG. 1 is a front perspective view of an object holder for pegboard mounting showing my new design;
FIG. 2 is a top plan view thereof;
FIG. 3 is a front elevational view thereof;
FIG. 4 is a side elevational view thereof, the side opposite being a mirror image thereof.

FIG. 1

FIG. 2

FIG. 4

FIG. 3
